(57) **CLAIM**

The ornamental design for an electric receptacle, as shown and described.

DESCRIPTION

This application is entitled to the benefit of and incorporates by reference essential subject matter disclosed in U.S. Non-provisional application Ser. No. 12/913,956, filed Oct. 28, 2010.

FIG. 1 is a front, top, left-hand side perspective view of an electric receptacle of a new, original and ornamental design;

FIG. 2 is a front view thereof;

FIG. 3 is a rear view thereof;

FIG. 4 is a right-hand side view thereof;

FIG. 5 is a left-hand side view thereof; and,

FIG. 6 is a top view thereof.

No claim is being made to the bottom view of the embodiments, therefore, none has been shown.

The broken lines shown in the drawings illustrate unclaimed portions of the article and form no part of the claimed design.
